UNITED STATES PATENT OFFICE.

MAXIMILIAN F. BONZANO, OF PHILADELPHIA, PENNSYLVANIA.

RAIL-FASTENING.

No. 923,009.

Specification of Letters Patent.

Patented May 25, 1909.

Application filed January 14, 1909. Serial No. 472,368.

To all whom it may concern:

Be it known that I, MAXIMILIAN F. BONZANO, a citizen of the United States, residing in Philadelphia, Pennsylvania, have invented certain Improvements in Rail-Fastenings, of which the following is a specification:

My invention relates to fastenings designed for the purpose of securing rails to ties or other suitable supports; and the object of my invention is to provide an improved form of fastening designed more particularly for use in connection with metal wear-plates carried by the ties and upon which the rails rest, although capable of use with rail-chairs having an upper surface to receive the rail and provided with shoulders to engage the fastenings.

My present form of fastening is designed to permit adjustment of the rail from one portion of the wear-plate to the other, the flange of the rail engaging, in each instance, one of the shoulders of such wear-plate, or a projection of the clip, on one side, and a portion 25 of the clip, or a removable member employed therewith and interposed between said base flange and the clip on the other side.

When the wear-plate is provided with shoulders through which the fastening bolts, screws or other means are passed, the top surfaces of the shoulders may be beveled or otherwise shaped in order that those clips which have no projections engaging said shoulders may be held against displacement 35 by correspondingly beveled or other shaped faces, and such beveling may be in either direction.

If desired the means securing the wear-plate to the tie may be provided with adjustable washers of the type illustrated in my patent dated Dec. 15, 1908, No. 906,860, to permit adjustment of said wear-plate with respect to the tie and thus increase the adjustability of the fastening and the consequent lateral placing of the rail with respect thereto to permit the maintenance of the gage at all times. This is accomplished without affecting the relative position of the means securing the wear-plate to the tie, nor 50 of the bolts of the rail securing means carried by said wear-plate. When the heads of these bolts are let into the top surface of the tie, it is only necessary to turn them to meet the changed position of the wear-plate without the necessity of boring the tie to provide 55 fresh recesses.

Other features of my invention will be more fully pointed out hereinafter, reference being had to the accompanying drawings, in which:

Figure 1, is a sectional view on the line *a—a*, Fig. 2, of one form of rail fastening means embodying my invention; Fig. 2, is a plan view of the same; Fig. 3, is a sectional view on the line *b—b*, Fig. 4, similar to Fig. 1, showing another form of rail fastening means embodying my invention; Fig. 4, is a plan view of the same; Figs. 5 and 6, are sectional views similar to Figs. 1 and 3, illustrating other forms of rail fastening means 70 embodying my invention; Fig. 7, is a sectional view similar to Figs. 1 and 3, of a still further modification, in which provision is made for adjusting the wear-plate, the latter being shown in section on the line *c—c*, Fig. 75 Fig. 8, is a plan view of the wear-plate shown in Fig. 7; Fig. 9, is a sectional view of the same character as Figs. 1 and 3, showing the application of my improved fastening to a metallic tie; means being provided for insulating the wear-plate and rail from the tie; Fig. 10, is a sectional view similar to Fig. 9, illustrating a modified form of wear-plate, and Figs. 11 to 22, both inclusive, are perspective views of clips and filling pieces 85 forming part of the several forms of rail fastening devices embodying my invention.

In all forms of my improved fastening devices I employ a wear-plate arranged to be secured to the tie either by independent fastening means such as screw bolts, or by the bolts or screws securing the fastening devices to the rail, or in some instances by both means; such wear-plate having shoulders paralleling the rail to be engaged by the clips 95 or projections on the same, and in some instances by the base flange of the rail. The clips are secured to the wear-plate and in contact with the rail flanges either by screw bolts which also enter the tie or by means of 100 bolts carried only by the wear-plate. The apertures in the wear-plates may be variously arranged depending upon the form of fastening device to be employed therewith, but in all instances the apertures of a particular plate are preferably set in regular order and in the same relative position in order to permit complete interchangeability of said wear-plates as well as the clips when the rail is being shifted laterally with respect 110 to such wear-plate.

In securing the rail to the wear-plate, in

the original use of the latter, it is set to one side; the clips on opposite sides in engagement with the rail-flanges being of different dimensions in order that when the rail is subsequently shifted in changing the gage of the track or the position of the rail, the clips can have their positions reversed and will then serve to secure the rail in place in the same manner as it was originally held.

10 The wider clips may have integral portions disposed between the rail flanges and the shoulders of the wear-plates, or independent filling pieces may be employed to suit conditions.

15 In some instances it may be desirable to employ wear-plates capable of adjustment in connection with the adjustable clips thereby increasing the scope of the fastening and the range of its adjustment. In other 20 instances it will be desirable to employ the wear-plates with metallic ties. In such case a block of resilient material, preferably wood, may be interposed between the wear-plate and the tie and the means for securing 25 the wear-plate to the tie may be insulated from such tie in order that the rail may be employed in any desired electrical circuit.

In Figs. 1 and 2 of the drawings, 1 represents a rail having base flanges 2, mounted 30 on a wear-plate 3, carried by a tie 4. The wear-plate is provided with shoulders 5 paralleling the rail; and adapted to engage said shoulders and overlie the base flanges 2 of said rail, are clips 6 and 7, clearly illustrated 35 in Fig. 1, and in the perspective views, Figs. 11 and 12, which clips differ in length, as clearly indicated in the drawing, so that the rail may be disposed to one side of the wear-plate, and are interchangeable in order to 40 provide for lateral adjustment of the rail to maintain the gage of the track. The clips 6 and 7 may be secured in place by bolts carried by the wear-plate; the latter being secured to the tie by suitable means, such as 45 spiking or by means of lag screws, or I may employ lag screws 8 which will serve to hold the clips to the rail and at the same time secure the wear-plate in proper position to the tie. Similar lag screws 9 may be employed 50 to secure the wear-plate to the tie and with such screws, washers 10 shown in Figs. 2 and 13, are preferably used.

The clip 6 may be provided with a depending portion 11 to engage one shoulder 55 of the wear-plate and lie between the same and the base flange of the rail, or I may provide the clip with a narrower depending portion and employ a filling piece between the same and the shoulder of the wear-plate. 60 The clip is apertured at 12 for the passage of a bolt, or the lag screw 8 in the manner shown; such aperture passing through the depending portion 11, and said clip is further provided with a depending portion 13, disposed at right angles to the rail, forming a lip

which extends over and engages the end of the wear-plate and the shoulder of the same. This lip serves as an additional holding means tending to retard creeping action of the structure and preventing shearing action 70 upon the bolts.

The clip 7 is shorter than the clip 6 and is provided with a depending portion 11 as indicated, somewhat narrower than that carried by the clip 6. Like the clip 6, the clip 7 75 is apertured through the depending portion 11 which is adapted to lie between the base flange of the rail and the shoulder of the wear-plate, so that when the rail is mounted upon the wear-plate and the clips with the 80 different width depending portions are in place, the rail will be disposed to one side of said wear-plate. The clip 7 may also be provided with a depending lip or projection 13 at its side to engage the end of the wear- 85 plate and the shoulder of the same. The clips are interchangeable, so that by shifting the same, the rail may be secured at one side or the other of the wear-plate, and by this means, adjustment of the rails to maintain 90 the gage of the track is provided for.

In the form of structure shown in Figs. 3 and 4, the shoulders 5 of the wear-plate are somewhat wider than those shown in connection with the wear-plate shown in Figs. 1 and 2, and are apertured for the passage of screws or bolts designed to hold the clips in engagement with the base flanges of the rail. In this form of the structure I employ clips 6^a and 7^a, shown in the inverted perspective 100 views, Figs. 14 and 15, each of which clips lies on top of the shoulder of the wear-plate and the flange of the rail. In the use of such clips, except for the possible use of the end flanges engaging the end and shoulder of the 105 wear-plate, they would be unsecured against lateral rotative movement. To avoid the danger of such movement, I may bevel the surface of the wear-plate shoulders in the manner shown, and bevel the clips accordingly; and, if desired, these clips may have in addition the depending portions 13 at the sides to engage the ends and shoulders of the wear-plate. The clips 6^a and 7^a are interchangeable as in the structure shown in Figs. 110 1 and 2, and the clip 6^a instead of having an integral depending portion lying between the edge of the rail flange and the shoulder of the wear-plate, may have a removable filling piece.

The wear-plate shown in Fig. 4, is provided with four apertures in the usual manner, but is illustrated as being held to the tie by the lag screws 8 securing the clips in place. In some instances such means may be sufficient without the use of bolts or screws to retain the wear-plate to the tie independently of the clip holding means.

In the structure shown in Fig. 5, the shoulder of the wear-plate is of a slightly 120

different width than either of those shown in Figs. 1 and 2, or Figs. 3 and 4, and the apertures for the bolts or lag screws pass directly through the edge of the shoulder, in the manner shown. If desired, the clips 6^b and 7^b may be apertured in the same way. In this instance, the shoulders of the wear-plate are beveled, in a direction opposite to that shown in Fig. 3, and as the clips may be provided with depending portions 13 in engagement with the shoulder of the wear-plate, they are held against movement when the fastening means are finally secured in place.

The clips 6^b and 7^b shown in Fig. 5, are shown in perspective; inverted, in Figs. 16 and 17. The clip 6^b has a depending portion 11, integral therewith to fill the space between the shoulder of the wear-plate and the flange of the rail. If desired, however, the depending portion may be narrower and a separable filling piece of uniform cross section throughout its length may be interposed between it and the base flange of the rail.

In Fig. 6, I have shown a sectional view, and in Fig. 18, a perspective view of a modified form of clip which need not be moved from side to side of the rail when it is desired to adjust the same laterally, but may simply be turned in its position when the bolt or lag screw 8 is backed off. This clip is indicated at 6^c, and is provided with horizontal projections 14 and 14^a, adapted to overlie the flanges of the rail and the shoulders of the wear-plate respectively. The projections 14 are longer than the projections 14^a so that when applied to a rail, each clip lies in the same position, as clearly illustrated in Fig. 6. In the use of such clip, inasmuch as the depending portion 11 is narrow, it is desirable to employ a separable spacing or filling member 15, interposed between said depending portion 11 and the flange of the rail. This separable spacing member may have hooked ends 16, as shown in Fig. 19, adapted to engage the sides of the clip, or hooked ends extending in opposite directions, one of which, 16 engages the clip, while the other 16^a engages the side of the wear-plate. As these clips are arranged to turn in their places, they cannot be provided with depending ribs or projections designed to engage the ends of the shoulders of the wear-plate in the manner shown with respect to the other views.

In Figs. 7 and 8, I have shown a form of wear-plate having means for adjusting the same with respect to the tie. Such means comprise washers 20, having bolt or screw holes 21 eccentrically disposed with respect to the washers, which are adapted to apertures 22 in the wear-plate. The bolts or screws serving to secure the wear-plate to the tie pass through these washers, and by shifting the latter the wear-plate may be adjusted without changing the position of the rail with respect to the same, but altering the po-

sition of such rail with respect to the tie. The bolts which secure the clip to the wear-plate may have cylindrical heads 23 engaging recesses 24 in the tie, and when the wear-plate is provided with the adjustable washers the heads of such bolts may be offset with respect to the shank of the same so that by simply turning said bolts the heads may fit the same recesses when the wear-plate has been re-adjusted by shifting the position of the washers with respect to the same. This adjustment of the wear-plate increases the flexibility of the fastening and provides an additional adjustment for the rail that may be somewhat less than that provided for by the changing of the clips. When the wear-plate is shifted by reversing the position of the washers 20, it is only necessary to turn the heads of the bolts 8^a securing the clips to the wear-plate in their seats so as to bring the shanks of said bolts in proper position to pass through the apertures of the wear-plate. In this form of my improved rail fastening, the clips are of the same general character as those shown in Figs. 1 and 2, except that the filling or spacing member 15 is shown as employed therewith. Fig. 7, also shows the washer for the lag screw 8, securing the wear-plate to the tie; such washer spanning the space between the shoulder of the wear-plate and the flange of the rail.

In Fig. 9, I have shown the application of my improved rail fastening means to a metallic tie, in which the means securing the wear-plate to the tie is insulated from the latter. In this instance the wear-plate is carried by a resilient block 25 as illustrated in my prior patents, which block may be of insulating material so that it is only necessary to employ as additional insulating means, a sleeve 26, encircling the bolts 27 employed for securing the wear-plate and block 25 to the tie.

In Fig. 10, I have shown a form of wear-plate in which the bolts 8^b for holding the clips in engagement with the rail flanges are provided with heads 28 arranged to fit countersunk recesses 29 in the underside of the wear-plate. For such purpose the wear-plate is made somewhat thicker than those illustrated in the other views.

In Figs. 7, 9 and 10, the clips 6 are shown in connection with the filling or spacing member 15, and in Figs. 21 and 22, I show perspective views of such clip with the filling piece 15 applied thereto in the relative position of use. In these views both forms of said filling piece are shown.

The clips employed in my several forms of fastening are clearly shown in the several perspective views, and it is to be understood that in each instance the clips employed with any single form of fastening are always interchangeable.

In the use of my present form of rail fas-

tening, it is of particular value for use in connection with track on curves. I may employ a structure of the type illustrated in my patent of December 15, 1908, before referred to for securing one rail, and a fastening of any of the types hereinbefore described and shown in the accompanying drawings for the other rail.

When bolts are employed to secure the clips to the wear-plate, the latter may be held to the tie by suitable securing means of any approved type, but when lag screws which pass through the wear-plate are employed in connection with the clips, they may be the sole holding means except the possible use of projections on the under side of the wear-plate to engage recesses in the top of the tie; such projections being preferably cylindrical in order that the recesses with which they engage may be made by boring.

I may also employ locking washers of the type illustrated in my pending application, Serial No. 467,859, filed December 16, 1908, for engagement with the heads of the several lag screws or bolts.

I claim:

1. A rail fastening comprising a wear-plate suitably secured to a tie, and clips carried by said wear-plate adapted to overlie the flange of a rail and secured to said wear-plate, said wear-plate having shoulders and the clips having portions disposed between the flange of the rail and the shoulders of the wear-plate, said clips being of different dimensions whereby lateral movement of the rail is provided for when said clips are adjusted.

2. A rail fastening comprising a wear-plate secured to a tie, said wear-plate having shoulders on each end which shoulders are apertured, clips carried by the wear-plate and overlying the flange of the rail, said clips being secured by fastening means passing through the apertured shoulders of the wear-plate, said clips being of different dimensions whereby lateral adjustment of the rail is provided for when said clips are interchanged, one of said clips having a filling portion lying between the rail flange and the flange of the wear-plate.

3. A rail fastening comprising a wear-plate secured to a tie, said wear-plate having shoulders or flanges on each end which shoulders are apertured, said shoulders being spaced farther apart than the width of the flanges of the rail laid between them, clips carried by the wear-plate and overlying the flange of the rail, said clips being secured by fastening means passing through the apertured shoulders of the wear-plate, said clips being of different dimensions whereby lateral adjustment of the rail is provided for when said clips are interchanged, one of said clips having a filling portion lying between the rail flange and the shoulder of the wear-plate.

4. The combination, in a rail fastening, of a wear-plate having beveled shoulders at the sides of the same paralleling the rail, a rail mounted on said wear-plate and having a base less in width than the space between the shoulders of the wear-plate, clips for securing said rail to the wear-plate, said clips being shaped to lie on the shoulders of the wear-plate, and means for holding said clips to the wear-plate and the latter to the tie. 75

5. The combination, in a rail fastening, of a tie, a wear-plate mounted upon said tie and having shoulders, a rail mounted upon said wear-plate, means for securing said wear-plate to the tie, clips engaging the shoulders of the wear-plate and the base flanges of the rail and designed to hold the latter to the wear-plate, and a removable filling piece retained in place by one of said clips and disposed between the base flange of the rail and one of the shoulders of the wear-plate. 85

6. As a new article of manufacture, a rail fastening for use with shouldered wear-plates, comprising a clip arranged to engage the top of the rail flange and the shoulder of the plate, and a filling piece interposed between the clip and the side of the rail flange. 90

7. The combination of a tie, an adjustable wear-plate mounted thereon, shoulders carried by said wear-plate, interchangeable clips 95 carried by said plate and serving to hold a rail in different positions with respect thereto, said clips being interposed between said shoulders and the flanges of the rail, and means for securing said clips to the wear-plate. 100

8. A rail fastening comprising a metal rail support, clips carried by said support and secured thereto for engagement with the flanges of a rail, said support having shoulders, and the clips having portions disposed between the flanges of the rail and the shoulders of its support, said clips being of different dimensions and interchangeable with respect to the rail and its support whereby 110 lateral movement of the rail is provided for when the position of said clips is transposed.

9. A rail fastening comprising a shouldered wear-plate suitably secured to a tie, interchangeable clips carried by said wear-plate adapted to engage the shoulders of the same and overlie the flanges of a rail, and means for securing said clips to the wear-plate, said clips being of different dimensions whereby lateral movement of the rail is provided for by shifting said clips. 115 120

10. As a new article of manufacture, a rail fastening for use with wear-plates, comprising a clip arranged to engage a rail flange, and a separable filling piece interposed between the clip and said rail flange. 125

11. A rail fastening comprising a shouldered wear-plate suitably secured to a tie, interchangeable clips carried by said wear-plate adapted to engage the shoulders of the 130

same and overlie the flanges of a rail, means for securing said clips to the wear-plate, said clips being of different dimensions whereby lateral movement of the rail is provided for when said clips are adjusted, and means for adjusting said wear-plate.

12. As a new article of manufacture, a rail fastening for use with wear-plates, comprising a clip arranged to engage a rail flange, and a separable filling piece of uniform cross

section throughout its length combined with said clip.

In testimony whereof, I have signed my name to this specification, in the presence of two subscribing witnesses.

MAXIMILIAN F. BONZANO.
